UNITED STATES PATENT OFFICE.

THOMAS CASCADEN, JR., OF WATERLOO, IOWA.

DESIGN FOR A FURNACE.

SPECIFICATION forming part of Design No. 22,403, dated May 2, 1893.

Application filed December 22, 1892. Serial No. 456,102. Term of patent 14 years.

To all whom it may concern:

Be it known that I, THOMAS CASCADEN, Jr., a citizen of the United States, residing at Waterloo, in the county of Black Hawk and State 5 of Iowa, have invented and produced a new and original Design for Furnaces or Heaters for Agricultural Boilers, of which the following is a specification, reference being had to the accompanying drawing, forming part thereof.

10 The figure is a perspective view of a heater or furnace for agricultural boilers constructed in accordance with my design.

The leading features of my design consist in the heater or furnace the shape and ornamentation of the same being formed with swelled sides having projecting lugs to which the handles are attached, and a raised front plate located above the door of the furnace,

said raised or stamped plate forming a rectangular panel in the center of which is a five-pointed star. The furnace door is also provided with a panel upon which scrolls are stamped as shown, and the shelf below this door is provided near each end with a five-pointed star. The swelled sides of the furnace are also provided with stars as shown.

The features of the design which I claim fully appear in the drawing.

What I claim is—

The design for a furnace as herein shown 30 and described.

THOMAS CASCADEN, JR.

In presence of—

THEODORE A. JENNEY,
WM. C. LOGAN.
